UNITED STATES PATENT OFFICE.

WALTER DOUGLAS LA MONT, OF THE UNITED STATES NAVY, ASSIGNOR, BY DIRECT AND MESNE ASSIGNMENTS, TO LA MONT WASTE HEAT STEAM GENERATOR CORPORATION, OF NEW YORK, N. Y., A CORPORATION OF NEW YORK.

STEAM GENERATOR.

Application filed December 28, 1918. Serial No. 268,651.

REISSUED

To all whom it may concern:

Be it known that I, WALTER D. LA MONT, United States Navy, a citizen of the United States, residing at Annapolis, in the county 5 of Anne Arundel, State of Maryland, have invented certain new and useful Improvements in Steam Generators, of which the following is a description, reference being had to the accompanying drawings, forming 10 a part hereof.

My invention relates to methods of and means for generating steam and has for its object a method of generating steam by which steam at high pressure adapted for 15 use in steam engines may be generated quickly from a small amount of water constantly supplied so that the weight of water carried in the generator during the process of generating the steam will be the least 20 possible and will add as little as possible to the weight of the generator itself. The invention also has for its object to provide a steam generator adapted to carry out the method described which will be simple in 25 construction, compact and of relatively light weight and will be adapted to effectively and safely generate steam rapidly and at high pressure from a relatively small amount of water.

30 My invention is particularly intended for generating steam for a steam engine for use in driving the propeller of an aeroplane. The advantages of a steam engine for this purpose over the explosion engine, particularly as regards possibility of continuous 35 operation for many hours, long life of the engine as a whole, freedom from vibration and the fatigue of the metal of the engine shaft and other parts affected by vibration, as well as other advantages, have long been 40 recognized but it has not heretofore been found possible to produce an engine and generator, which, when in operation, that is with water in the generator, would be sufficiently light in weight to be used. The diffi- 45 culty so far as the engine itself is concerned has been overcome, it being possible to construct engines of the turbine type which are sufficiently light in weight per horse power furnished for use in an aeroplane; and the condenser also presents no difficulty at it is possible to design a condenser of the honeycomb type sufficiently light for the purpose. The serious difficulty has been in

the generator. Generators which have been 55 constructed of relatively light weight in themselves have been found when in use, that is, when supplied with the water necessary for effective operation, of a weight much too great to permit of their being used 60 in an aeroplane.

By the use of my invention it is possible to generate steam in sufficient quantity and at sufficient pressure to effectively operate the engine of an aeroplane without exceeding 65 a weight, for generator and the water contained in it during the process of generating steam, which is well within the limit permissible for use in aeroplanes and it is also possible to superheat the steam generated so as to deliver it to the engine at any 70 temperature and pressure desired.

With the above described objects and others hereinafter set forth in view, my invention consists in the method of and means 75 for generating steam hereinafter described and particularly pointed out in the claims.

Referring to the drawings—

Figure 1 is a longitudinal vertical sectional view of a steam generator adapted to carry 80 out my method and embodying my means for generating steam, the centrifugal spraying device being omitted.

Figure 2 is a top plan view of the generator shown in Figure 1. 85

Figure 3 is end view of the same.

Figure 4 is a central vertical cross-sectional view of the upper end of one of the generating tubes and the distributing tube showing the spraying nozzle strip in position. 90

Figure 5 is a side view of a portion of the locking strip for holding the spraying nozzle strip in position, and Figure 6 is a cross-section of the same on line 6—6 of Figure 5. 95

Figure 7 is side elevation of a portion of the spraying nozzle strip and Figure 8 is a cross-sectional view of the same in line 8—8 of Figure 7.

Figure 9 is a bottom plan view of a portion of the spraying nozzle strip shown in Figures 7 and 8. 100

Figure 10 is a top plan view of a portion of the spraying nozzle strip.

Figure 11 is a side elevation of a portion of the lining tube for the distributing tube and Figure 12 is a cross-section of the same on line 12—12 of Figure 11. 105

Figure 13 is a fragmentary sectional view similar to Figure 1, but showing the generator tubes merged in at their upper and lower ends where they are secured to the distributing pipe and the collecting pipe.

It should be understood that so far as concerns the method the drawings are illustrative merely and are not intended to limit the invention to the use of the apparatus shown or to any particular form or construction of apparatus.

In the drawings, 1 indicates a distributing tube at the upper end of the generator closed at one end and having connected to it 15 at the other end by coupling 2 a pipe 3 leading from a header pipe 4 to which leads a water supply pipe 5 from a feed pump 6, preferably a centrifugal pump. 7 indicates a collecting pipe near the lower end of 20 the generator closed at one end and connected at its other end by coupling 8 to a pipe 9 leading to a header pipe 10 from which a pipe 11 leads to a separator 12 for separating the steam from the water dis- 25 charged from the collecting pipe 7. From this separator a pipe 13 leads upward to the engine, not shown, but preferably of the turbine type, and from the lower end of the separator a suitably valved pipe 14 leads to 30 the pump 6 to take the water separated from the steam back to the pump to be again supplied to the distributing pipe 1.

From the distributing pipe 1 to the collecting pipe 7 extend a series of generator 35 tubes 15 suitably secured by welding or otherwise at their ends in the pipes 1 and 7. In actual construction, each of these tubes is 15 feet long, is one-half inch in exterior diameter, of seamless drawn steel with walls twenty-eight thousandths of an inch thick but, of course, the length and diameter and other dimensions may be varied as desired. These tubes are arranged at equal distances apart along the tubes 1 and 7, preferably so 45 that their outer surfaces will be separated one from the other approximately one-fourth inch. In the construction shown, there are six of the distributing tubes 1 and collecting tubes 7, each distributing tube being connected with the header pipe 4 and each collecting tube being connected to the header pipe 10. For compactness alternating distributing pipes are elevated above the intermediate ones, the same arrangement 50 being followed with the collecting pipes. The tubes 15 connected with one distributing pipe 1 are arranged opposite the spaces between the tubes 15 connected with the next adjacent distributing pipe.

60 The tubes 15 with their distributing pipes and collecting pipes are enclosed in a suitable casing 16, preferably open at the top and consisting of kieselguhr composition on a wire netting. This casing extends below 65 the collecting tubes 7 to form a combustion

chamber 17 into which a series of oil atomizing burners 18 discharge, the flame playing upward through the spaces between the tubes 15 and heating them to a high temperature.

The construction thus above described would be an effective steam generator but if the tubes 15 are filled with water as would usually be expected the weight of the generator in operation would be too great to permit of its use on an aeroplane.

In order to avoid the filling of the tubes with water and thus avoid the consequent weight as well as to secure other important advantages

hereinafter more fully set forth, I provide, in accordance with my invention, for so distributing the water in each of the tubes 15 that it will form a thin coating or film on the inner surface of each tube, which will be

maintained as a continuous film from the distributing tube 1 to the collecting tube 7, or nearly to the collecting tube if it is desired to superheat the steam as hereinafter explained, so as to leave a central passage

open at its lower end into which the steam generated from the film may escape as it is formed and may pass freely to the collecting tube. By reason of the fact that the

water is thus in a thin layer or film, steam is generated rapidly and it is found possible to evaporate a much greater amount of water per unit of surface per unit of time than would be possible to evaporate if the tubes were filled with water, and it is also

possible to deliver the steam downward without an excessive amount of water.

From the distributing pipe 1 to the collecting pipe 7 extend a series of generator

tubes 15 suitably secured by welding or otherwise at their ends in the pipes 1 and 7. In actual construction, each of these tubes is 15 feet long, is one-half inch in exterior diameter, of seamless drawn steel with walls twenty-eight thousandths of an inch thick but, of course, the length and diameter and other dimensions may be varied as desired. These tubes are arranged at equal distances apart along the tubes 1 and 7, preferably so

that their outer surfaces will be separated one from the other approximately one-fourth inch. In the construction shown, there are six of the distributing tubes 1 and collecting tubes 7, each distributing tube being connected with the header pipe 4 and each collecting tube being connected to the header pipe 10. For compactness alternating distributing pipes are elevated above the intermediate ones, the same arrangement

being followed with the collecting pipes. The tubes 15 connected with one distributing pipe 1 are arranged opposite the spaces between the tubes 15 connected with the next adjacent distributing pipe.

The tubes 15 with their distributing pipes and collecting pipes are enclosed in a suitable casing 16, preferably open at the top and consisting of kieselguhr composition on a wire netting. This casing extends below

the collecting tubes 7 to form a combustion

chamber 17 into which a series of oil atomizing burners 18 discharge, the flame playing upward through the spaces between the tubes 15 and heating them to a high temperature.

The construction thus above described would be an effective steam generator but if the tubes 15 are filled with water as would usually be expected the weight of the generator in operation would be too great to permit of its use on an aeroplane.

In order to avoid the filling of the tubes with water and thus avoid the consequent weight as well as to secure other important advantages

hereinafter more fully set forth, I provide, in accordance with my invention, for so distributing the water in each of the tubes 15 that it will form a thin coating or film on the inner surface of each tube, which will be

maintained as a continuous film from the distributing tube 1 to the collecting tube 7, or nearly to the collecting tube if it is desired to superheat the steam as hereinafter explained, so as to leave a central passage

open at its lower end into which the steam generated from the film may escape as it is formed and may pass freely to the collecting tube. By reason of the fact that the

boilers or generators in which the water is sprayed against highly heated surfaces in quantity only sufficient to insure substantially instantaneous complete volatilization, 5 thermostatic means being usually provided to effect an automatic control of this quantity.

Among the advantages of the method of the present invention is that the generation 10 of the steam from a film on the inner wall of the tube in contra-distinction to the explosive action of flash generation is more uniform and continuous and does not require the careful regulation that is necessary with the "flash" boiler. Moreover, the present invention permits the employment of relatively thin tubes, permitting a very rapid heat exchange without danger of the tubes being burned out, the film of water 15 protecting the tubes against this.

When the generator of the present invention is operated in the preferred manner, the film is caused to extend substantially to the lower end of the tube so that water and 20 steam are discharged together at this end, thereby avoiding any necessity for accurate control of the water feed which, as above pointed out, is requisite in "flash" boilers. The generator of the present invention operates with a very high degree of efficiency 25 under varying demands with a minimum control of the water feed.

There are thus combined in this steam generator the advantage of light weight incidental to the use of relatively small quantities of water in the generating tubes in the process of steam generation, the advantage of protection afforded to the tubes by the maintenance of a film of water on the inside 30 thereof during the generation of the steam, and the advantage of doing away with the necessity for careful variation of the water feed to meet varying demands made upon the generator.

For the purpose of causing the water to be introduced into the tubes 15 in such manner as to form a film on the interior surface of the tubes, any convenient form of distributing or spraying device which will 35 cause the water to be sprayed against the walls may be used, but the device which I prefer to use for this purpose consists of a nozzle having a chamber 20 of relatively large diameter directly above the tube 15 having a discharge orifice 21 of relatively small diameter in line with the axis of the tube, in which the water is admitted to the chamber 20 through passages 22 arranged at 40 tangents to the periphery of the chamber so as to cause the water as it enters the chamber to whirl or rotate and to be discharged through the orifice 21 as a rotating stream throwing the water as a centrifugal spray against the walls of the tube. The chamber 45 20 is preferably formed in a solid piece of

metal through which passages 23 lead to the outer ends of the tangential passages 22.

Each of the distributing tubes 1 has connected with it a considerable number of tubes 15. In the construction shown each 50 distributing tube carries seventeen tubes 15. In order to provide a spraying nozzle for each of these tubes, I form the necessary number of chambers 20 at distances apart corresponding to the distance apart of the 55 tubes, in the lower or convex surface of a semicircular strip 24 and form in this lower or convex surface the tangential passages 22 as grooves leading from the passages 23 which extend through the strip to the upper 60 or flat face. This semicircular strip fits within a tube 25 which fits within the distributing tube 1 and has formed in it at such intervals that when in position each one will be in line with the axis of a tube 15, the discharge orifices 21. The semicircular strip 65 24 is held in position in the tube 25 by a semicylindrical locking strip 26 or by other convenient means. The diameter of the chamber 20 is preferably about one-fourth 70 of an inch in diameter but may be larger. The discharge orifice 21 is preferably about four hundredths of an inch in diameter. 75

In operation water is forced by the feed pump 6 through the pipes shown into the 80 space above the nozzle strips 24 within the inner tubes 25 in the distributing pipes 1, and through passages 23 and tangential passages 22 into chambers 20 and enters the upper 85 ends of the tubes through discharge orifices 21 in the form of a centrifugal spray thrown outward against the walls of the tubes and forming on these walls a thin layer or film. So long as the pressure on the water exceeds the pressure of steam in the 90 tubes water will be forced into the ends of the tubes and will form a film as described and this film will extend as a continuous film throughout the length of the tube or such 95 part of the length of the tube as may be desired, depending on the excess of the pressure on the water over the pressure of the steam generated. For ordinary purposes the pressure on the water should be such that 100 the film will extend to the lower ends of the generator tubes and water and steam will be discharged together into the collecting tubes. In a generator in which steam is to be generated at a pressure of 800 pounds it 105 is desirable to use a pressure on the water of 200 pounds in excess of the 800 pounds that is at 1000 pounds. If it is desired to superheat the steam the pressure on the water is reduced so that the film will not 110 extend to the lower ends of the generator tubes so that the steam generated from the film will come in contact with the walls of the generator tubes below the film and in the 115 collected tubes and will be superheated by 120 such contact. 125

From the collecting tubes the water and steam passes to the separator from which the steam passes by pipe 13 to the engine and condenser from which the water of condensation is returned to the feed pump by pipe 27 by which is also supplied, as may be required, water from the make up feed. The water separated from the steam in the separator 12 passes by pipe 14 to the feed pump which it enters at nearly the temperature at which it came from the generator and is returned to the distributing tubes at substantially this temperature, thus entering the generator tubes highly heated. If the steam is superheated, as above described, there will, of course, be no water to be separated from the steam and the feed pump will be supplied from the condenser.

The high pressure of the steam in the generator tubes stiffens the tube against any tendency of the tube to buckle from any unevenness of heating. The free escape of the steam, as it is generated through the passage at the center of the tube, facilitates the rapid and continuous evaporation of the water and thus permits of and necessitates a very rapid feed in order to maintain the film throughout or substantially throughout the length of the generator tubes. The water is thus required to and does circulate rapidly in contact with the heated surfaces of the tubes, a condition which facilitates effective generation.

The length of the generator tubes corresponds to the vertical distance between the two planes of the biplane on which it is to be used, the open upper end of the casing 16 extending through the upper plane so that the products of combustion will be discharged above this upper plane. The relatively great lengths of the generator tubes permits of utilizing a very high percentage of the heat produced by the burners.

While, as above stated, the invention is particularly adapted and intended for use in connection with aeroplane engines, it is obviously adapted for use in connection with steam generators for other purposes and may readily be adapted to any water tube type of boiler in which the tubes are arranged other than horizontal, that is, are so arranged that one end is substantially higher than the other so that the film formed on the interior of the tubes will be free to move downward and will be aided in its movement by gravity.

Claims to certain separable subject matter common to this application and to my pending application, Serial No. 32,064 filed May 22, 1925, will be made in my said pending application.

Having thus described my invention what I claim is:

1. The method of generating steam, which consists in forcing water into the upper end

of a heated tube having one end higher than the other, and directing the water toward the wall of said tube, said water being continuously introduced in such quantity as continuously to maintain a film on said wall throughout a substantial portion of the length of the tube and to leave the center of the tube unobstructed, and discharging from the lower end of the tube the steam and unevaporated water arriving at said end. 75

2. The method of generating steam, which consists in continuously forcing water into the upper end of a heated tube having one end higher than the other and against the inner wall of said tube in such quantity and at such pressure in proportion to the heat of the tube as will continuously maintain a film on said wall substantially throughout the length of the tube, while leaving the center of the tube unobstructed, and discharging the steam generated from said film and the unevaporated water from the lower end of said tube. 80

3. The method of generating steam, which consists in forcing water into the upper end of a heated tube having one end higher than the other and against the inner wall of said tube in such quantity and at such pressure in proportion to the heat of the tube as will maintain a film on said wall substantially throughout the length of the tube, while leaving the center of the tube unobstructed, and discharging the steam generated from said film and the unevaporated water from the lower end of said tube and separating the steam from the water. 90

4. The method of generating steam, which consists in forcing water into the upper end of a heated tube having one end higher than the other and against the inner wall of said tube in such quantity and at such pressure in proportion to the heat of the tube as will maintain a film on the said wall substantially throughout the length of the tube, while leaving the center of the tube unobstructed, and discharging the steam generated from said film and the unevaporated water from the lower end of said tube, separating the steam, and returning the water to the upper end of the tube. 105

5. The method of generating steam in a heated tube having one end higher than the other, which consists in continuously forcing water into the upper end of said tube in a quantity greater than will be evaporated in the tube but less than sufficient to fill the tube and directing this water against the wall of the tube, thereby leaving the center of the tube unobstructed to receive the steam generated from the film of water thus formed upon the tube wall, and discharging the steam and unevaporated water from the lower end of said tube. 115 120

6. The method of generating steam in a tube of relatively great length in proportion 130

to its diameter and having one end higher than the other and its lower end open, which consists in heating said tube by heat-exchanging contact with heated gases travelling up the outside of said tube throughout substantially the whole length thereof, continuously forcing water into the upper end of said tube in quantity greater than will be evaporated in said tube but less than sufficient to fill the tube, directing this water against the inner wall thereof to form a film thereon, leaving the center of the tube unobstructed to receive the steam generated from said film, continuously discharging from the lower end of said tube the steam and unevaporated water reaching said end, and separating the steam from the water.

7. The method of generating steam in a tube having one end higher than the other, which consists in heating said tube by heat-exchanging contact with heated gases travelling up the outside of said tube throughout substantially the whole length thereof, continuously forcing water into the upper end of said tube in quantity greater than will be evaporated in said tube but less than sufficient to fill the tube, directing this water against the inner wall thereof to form a film thereon, leaving the center of the tube unobstructed to receive the steam generated from said film, and continuously discharging steam and unevaporated water from the lower end of said tube, separating the steam from the water, and returning said water to the upper end of said tube.

8. In a steam generator a substantially direct generator tube sufficiently inclined to the horizontal to insure rapid gravity flow and having its lower end open, means for heating the tube, means for continuously forcing water into the upper end of said tube and so directing it against the inner wall thereof as to form a film thereon and leave the center of the tube unobstructed, and means for separating the water from the mixture of steam and water discharged from the lower end of said tube.

9. In a steam generator a substantially direct generator tube sufficiently inclined to the horizontal to insure rapid gravity flow and having its lower end open, means for heating the tube, means for continuously forcing water into the upper end of said tube and so directing it against the inner wall thereof as to form a film thereon and leave the center of the tube unobstructed, means for separating the water from the mixture of steam and water discharged from the lower end of said tube, and means for conducting the separated water back to the upper end of said tube.

10. Apparatus for generating steam, comprising a series of substantially direct generator tubes sufficiently inclined to the horizontal to insure rapid gravity flow and

a distributing tube connected to the upper ends of said tubes, a collecting tube connected to the lower ends thereof, means for directing heated gases into heat-exchanging contact with said generator tubes throughout substantially the whole length thereof, means for forcing water under pressure through said distributing tube into the upper ends of said generator tubes in quantity greater than will be evaporated in the respective generator tubes, but less than sufficient to fill said tubes, means for so directing said water against the inner walls of said tubes as to form a film on said walls and leave the centers of the tubes unobstructed and means for separating the water from the steam and water collected in the collecting tube.

11. Apparatus for generating steam, comprising a series of substantially direct generator tubes sufficiently inclined to the horizontal to insure rapid gravity flow and a distributing tube connected to the upper ends of said tubes, a collecting tube connected to the lower ends thereof, means for directing heated gases into heat-exchanging contact with said generator tubes throughout substantially the whole length thereof, means for forcing water under pressure through said distributing tube into the upper ends of said generator tubes in quantity greater than will be evaporated in the respective generator tubes, but less than sufficient to fill said tubes, means for so directing said water against the inner walls of said tubes as to form a film on said walls and leave the centers of the tubes unobstructed, means for separating the water from the steam and water collected in the collecting tube, and means for returning said separated water to the distributing tube.

12. Apparatus for generating steam comprising a series of substantially direct thin tubes each of relatively great length compared with its diameter sufficiently inclined to the horizontal to insure rapid gravity flow and a distributing tube connected with the upper ends of said tubes, a collecting tube connected to the lower ends thereof, means for directing heated gases into heat-exchanging contact with said tubes from the lower to the upper ends thereof, means for forcing water under pressure through said distributing tube into the upper ends of the generator tubes in quantity greater than will be evaporated in the respective tubes but less than sufficient to fill them, means for so directing said water against the inner walls of said tubes as to form a film on said walls and leave the centers of the tubes unobstructed and means for separating the water from the steam and water collected in the collecting tube.

13. In a steam generator, a distributing

5 tube, a series of generator tubes communicating therewith and having their ends fastened therein; and a second removable tube within said distributing tube and provided with discharge orifices registering with the ends of said generator tubes which communicate with said distributing tube.

10 14. In a steam generator, a complete circuit for the water therein including a generating element through which the water gravitates, and a connection between the ends of said element through which the

unvaporized water is returned to the upper end thereof, means in said return connection for effecting the movement of the water therethrough, and means also in said return connection for separating the steam from the mixture of steam and water issuing from the lower end of said generating element.

15 20 In testimony whereof I affix my signature this 26th day of December 1918.

WALTER DOUGLAS LA MONT.
